INGWAL O. BLANKENBERG, OF MILWAUKEE, WISCONSIN

CHIMNEY SMOKE-PIPE THIMBLE

Application filed August 12, 1929. Serial No. 385,297.

This invention relates to improvements in chimney smoke pipe thimbles.

In connecting a furnace or boiler smoke pipe to a chimney it is common practice to 5 chop an opening in the bricks of the side wall of the chimney which opening is of necessity irregular, and then the flanged portion of a stove pipe thimble is cemented or plastered around said opening and the end portion of 10 the smoke pipe is received by said thimble. This arrangement is open to the disadvantages that the cement or plaster for securing the thimble is exposed and will crack away from the bricks and will ultimately destroy 15 the draft through the smoke pipe and also loosen the smoke pipe connection.

It is the primary object of the present invention to overcome the above objections by providing a device or thimble for securing 20 the end of a smoke pipe within a chimney opening in a manner so that the attachment cannot loosen and which can be installed and connected very expeditiously.

It is also an object of the invention to provide 25 a chimney smoke pipe connection or thimble which will not break away from the chimney when the smoke pipe is removed for cleaning or replacement.

A further object of the invention is to provide 30 a chimney smoke pipe thimble which is neat and attractive in appearance, is strong and durable, is inexpensive to manufacture and install, and is well adapted for the purposes described.

With the above and other objects in view 35 the invention consists of the improved chimney smoke pipe thimble and its parts and combinations as set forth in the claims, and all equivalents thereof.

In the accompanying drawing in which 40 the same reference characters indicate the same parts in all of the views:

Fig. 1 is a fragmentary view of a chimney showing the improved smoke pipe thimble 45 mounted in an opening therein and receiving the end portion of a smoke pipe, parts being broken away and in section;

Fig. 2 is a front view of the improved chimney smoke pipe thimble;

Fig. 3 is a rear view thereof;

Fig. 4 is side view thereof;

Fig. 5 is a detail perspective view of the square collar portion of the thimble; and

Fig. 6 is a detail perspective view of the flange portion of the thimble.

Referring now more particularly to the drawing it will appear that the device comprises a square stove pipe thimble designated by the numeral 8 and secured to the inner forward portions of the side walls of the 60 thimble are right-angular attaching brackets 9 whose projecting portions are formed with threaded openings 10. Adapted to co-operate with the thimble member 8 is a stove pipe collar 11 which is of square formation 65 and is of dimensions larger than those of the thimble and said collar 11 is formed with a central circular opening 12 of a size sufficient to closely receive the end portion of a standard smoke pipe.

When the device is installed, a square hole of a suitable size is chopped in the bricks of a wall of the chimney 13, said hole being designated by the numeral 14 in Fig. 1, and in practice the opening 14 is usually quite 75 irregular due to the difficulty in forming a hole in the brick wall. The square stove pipe thimble 8 is then inserted into the opening 14 so that its outer edge is flush with the outer surface of the chimney, as shown in 80 Fig. 1, and if there are any crevices between the thimble and the bricks surrounding the opening 14, the same may be filled with cement or mortar. Also, cement, mortar or plaster is disposed on the outer surface of 85 the chimney around the opening, as indicated by the numeral 15 in Fig. 1. It should also be observed that the thimble is anchored in place within the opening by means of spaced pairs of nails 16 driven through openings 17 90 therefor in the side walls of the thimble member, and into the mortar joints between bricks of the chimney.

After the thimble has been anchored with 95 in the chimney opening and cement, mortar or plaster has been disposed on the outer surface of the chimney around the opening, the outer collar 11, which is initially separated from the thimble 8, is pressed against the cement, with the opening 12 in the collar 100

coinciding with the opening 14 as closely as possible. The collar 11 is then connected to the thimble and drawn tightly against the mortar or cement interposed between the same and the wall of the chimney by means of bolts 18 inserted through openings 19 therefor in the collar member 11 and also through the openings 10 in the brackets 9 carried by the square thimble member, and the inner end portions of the bolts, of course, carry nuts 20. In this manner the outer collar member 11 is tightly connected to the inserted thimble member 8 and is clamped against the chimney wall and the cement or mortar interposed between the chimney wall and the collar seals any crevices or cracks which might occur. The outer end portion of a chimney smoke pipe 21 is lastly inserted into the opening 12 of the collar member 11 sufficiently far so that the external annular bead 22 of the smoke pipe will abut against the outer face of the collar member as shown in Fig. 1.

The improved chimney smoke pipe thimble provides an efficient and quick device for the securement of the inner portion of a smoke pipe within an opening cut in a chimney and there is no danger of the cement or mortar working loose or breaking away because it is clamped tightly between the inner surface of the collar member 11 and the outer surface of the chimney adjacent the opening therein. The device, furthermore, permits the quick detachment or attachment of a chimney smoke pipe when it is necessary to clean or replace the same, and there is no danger of the draft being destroyed by the occurrence of a leak in the chimney opening for the smoke pipe end. Also, the device is both simple and novel and is well adapted for the purposes set forth.

What is claimed as the invention is:

1. The combination with a chimney having an opening cut through a wall thereof, of a thimble member inserted in said opening flush with the outer surface of the wall, a collar of greater outside dimensions than said thimble member clamped to said thimble member against the outer surface of said chimney wall and having an opening therein registering with said chimney wall opening, cementitious material interposed between said collar and the chimney wall around the opening therein, and a smoke pipe having its end portion inserted in the opening of said collar.

2. In combination, a chimney having an opening cut through a wall thereof, a square thimble member inserted in said opening flush with the outer surface of the wall, means for anchoring said thimble member within the opening, a square collar member of greater outside dimensions than said thimble member clamped to said thimble member against the outer surface of said chimney

wall and having an opening therein registering with said chimney wall opening, cementitious material interposed between said plate and the chimney wall around the opening therein, and a smoke pipe having a beaded outer end portion frictionally mounted within said collar opening with the bead against the outer surface of the collar surrounding the opening.

In testimony whereof, I affix my signature.

INGWAL O. BLANKENBERG.
